UNITED STATES PATENT OFFICE

162,342

ELECTRIC CONTROL PANEL BOARD

Elwood T. Platz, William Robertson, and Louis W. Higgins, Detroit, Mich., assignors to BullDog Electric Products Company, Detroit, Mich., a corporation of West Virginia

Application April 13, 1948, Serial No. 145,698

Term of patent 14 years

(Cl. D26—13)

To all whom it may concern:

Be it known that we, Elwood T. Platz, William Robertson, and Louis W. Higgins, citizens of the United States and residents of Detroit, Michigan, have invented a certain new, original, and ornamental Design for an Electric Control Panel Board, of which the following is a specification, reference being had therein to the accompanying drawings.

In these drawings:

Fig. 1 is a front elevational view of an electric control panel board showing our new design,

Fig. 2 is a sectional view thereof taken on line 2—2 of Fig. 1,

Fig. 3 is an enlarged fragmentary front elevational view thereof.

Figs. 4 and 5 are perspective views of the top of a unit with the remainder portion being indicated by the dotted lines.

We claim:

The ornamental design for an electric control panel board, substantially as shown and described.

ELWOOD T. PLATZ.
WILLIAM ROBERTSON.
LOUIS W. HIGGINS.
